(57) **CLAIM**

The ornamental design for a mirrored hubcap assembly, as shown and described.

DESCRIPTION

FIG. 1 is a perspective view of the ornamental design for a mirrored hubcap assembly according to the present invention, with the separate physical elements of the mirrored hubcap assembly separated for visual reference.

FIG. 2 is a front view of the mirrored hubcap assembly shown in FIG. 1.

FIG. 3 is a back view of the mirrored hubcap assembly shown in FIG. 1.

FIG. 4 is a left-side view of the mirrored hubcap assembly shown in FIG. 1.

FIG. 5 is a right-side view of the mirrored hubcap assembly shown in FIG. 1, opposite the left-side view of FIG. 4.

FIG. 6 is a top view of the mirrored hubcap assembly shown in FIG. 1.

FIG. 7 is a bottom view of the mirrored hubcap assembly shown in FIG. 1; and,

FIG. 8 is a second perspective view of the mirrored hubcap assembly shown in FIG. 1, with the separate physical elements of the mirrored hubcap assembly connected to each other.

In FIG. 1, the dashed broken lines depict environment and form no part of the claim. The dot-dash broken lines represent the alignment lines of the parts of the mirrored hubcap assembly and form no part of the claim.
